UNITED STATES PATENT OFFICE

2,324,743

ADJUSTABLE GRILLE

Dallas Emery Walker, Tampa, Fla., assignor of
one-half to Donald Everett Walker, Tampa,
Fla.

Application February 21, 1941, Serial No. 380,054

10 Claims.

(Cl. 20—71)

My invention disclosed herein relates to new and useful improvements in adjustable door and window grilles.

It is an object of this invention to provide an improved grille arrangement whereby the same may be extended or contracted, adjusted horizontally or vertically, so that the grille may be adapted for convenient installation in windows or doors of varying size or shape by the simple adjustment of the grille without the necessity of cutting or difficult fitting operations.

Further it is an object of my invention to provide a grille arrangement having base bars forming a quadrangle mounted and secured within the opening of a door or window by other bars and attachment members independent of the base bars. The base bars, other bars and attachment members so arranged as to permit the greatest contraction and extension of the body of the grille.

Moreover it is an object of my invention to provide a plurality of fastening members for securing the grille to the frame of a door or window, which fastening members are so arranged that as the grille is extended or contracted the said attachment members will remain in alignment and will each be equally adjusted.

It is a further object of my invention to provide an independent means for extending or contracting the attachment members of my improved grille without extending or contracting the main body of the said grille and thereby providing greater latitude for the adjustment of my grille.

Also it is an object of my invention to provide an improved grille adapted to protect door screening and serving as a means for preventing the door from warping or sagging and further providing an additional safe guard and a burglar bar for doors or windows.

Other objects and advantages of my invention are set forth in the following description, taken with the accompanying drawings; and the novel features thereof are pointed out in the appended claims. The disclosure, however, is illustrative only and I may make changes in detail, especially in matters of shape, size and arrangements of parts within the principle of the invention, to the full extent indicated by the terms in which the appended claims are expressed.

On the drawings:

Figure 1 is a front elevation of my improved grille shown in position as applied to a door or window.

Figure 2 is a front elevation of the same grille extended vertically and contracted laterally so as

to fit within a narrower opening of greater height than that shown in Figure 1.

Figure 3 is a front elevation of the same grille contracted vertically.

5 Figure 4 is a front elevation of a modified form of my grille shown as applied to a window.

Figure 5 is a front elevation of the grille shown in Figure 4 extended vertically.

10 Figure 6 is a front elevation of the grille disclosed in Figure 4 vertically contracted.

Figure 7 is an elevation of the principal base bars shown in the form of my invention disclosed in Figure 1.

15 Figure 8 is an elevation of the supplemental base bars shown in the form of my invention disclosed in Figure 1.

Figure 9 is an elevation view of the double action extensible attachment member provided in my invention.

20 Figure 10 is an elevation view of the base bar structure of the form of my invention shown in Figure 4.

On the drawings the same numerals indicate the same parts throughout.

25 My improved grille herein disclosed is preferably formed of suitable metal strips twisted in a manner well known in the art so as to present at their points of crossing flat surfaces to each other, at which points the same are pivotally connected by rivets or other suitable means.

The embodiment of my invention illustrated in Figures 1, 2 and 3 has provided the principal base bar structure as shown in Figure 7 including the primary base bars indicated by numerals 1 and 2 and the secondary base bars indicated by the numerals 3, 4, 5 and 6.

30 The primary base bars 1 and 2 are crosswise disposed and pivotally connected at the center thereof as at 7.

40 The secondary base bars 5 and 6 are pivotally connected at the adjacent ends thereof. The opposite end of the bar 5 is pivotally connected at one end of the primary base bar 2 while the other end of the bar 6 is pivotally connected to one end of the primary base bar 1.

The secondary base bars 3 and 4 are likewise pivotally connected at the adjacent ends thereof and are likewise pivotally connected to the other

45 ends of the primary base bars 1 and 2 respectively. This structure as shown in Figure 7 provides a pair of equal sized oppositely positioned and pivotally connected quadrangles.

50 A supplemental base bar structure is further provided as shown in Figure 8 including two

pairs of supplemental base bars, 8 and 9, and 10 and 11, respectively.

Each base bar in each pair is disposed crosswise to the other base bar of the said pair and are pivotally connected thereto. Furthermore the supplemental base bar 9 is pivotally connected at one end to the adjacent end of the supplemental base bar 10 of the opposite pair and the supplemental base bar 8 is likewise pivotally connected at one end to the adjacent end of the supplemental base bar 11.

The supplemental base bar structure as shown in Figures 1 and 8 forms a third quadrangle having sides of equal length, pivotally interconnected with the two larger quadrangles formed by the principal base bar structure. The same are so positioned that the point of pivotal connection 7 between the two primary base bars is placed at the center of the said third quadrangle. The supplemental base bars 8 and 10 extend in parallel relationship to, equally distanced from and at opposite sides of the primary base bar 1, while the supplemental base bars 9 and 11 are similarly positioned with respect to the primary base bar 2. Moreover, each of the said supplemental base bars are in turn pivotally connected to the primary and secondary base bar extending crosswise thereto as at 16 and 17 respectively.

Further, at the free ends of the supplemental base bars 8, 9, 10 and 11 are provided curved or curled attachment members 18, 19, 20 and 21 respectively adapted to serve as a convenient means for attaching my improved grille structure to the frame of a door or window.

Further in the form of my invention illustrated in Figure 1 there are provided two pairs of primary attachment bars, one pair including the bars 22 and 23 and the other pair including the bars 24 and 25. The primary attachment bars of each pair are disposed in crosswise relation and pivotally connected as at 26 and 27.

The primary attachment bars 23 and 24 are pivotally fastened in opposite quadrangles, but extend in parallel relation to the primary base bar 1 while the primary attachment bars 22 and 25 are similarly fastened and extend in parallel relation to the primary base bar 2.

The said primary attachment bars are positioned between the parallel extending secondary base bar and the parallel extending supplemental base bar equally distanced therefrom and pivotally attached to the crosswise extending primary base bar, supplemental base bar, primary attachment bar and secondary base bar as shown in Figures 1, 2 and 3.

At the end of the said primary attachment bars 22, 23, 24 and 25, nearest the primary base bar, there are provided curved or curled fixed end attachment members 28, 29, 30 and 31 respectively adapted to serve as a convenient means for attaching the grille structure to the frame of a door or window.

At the other end of the said primary attachment bars there are provided extensible end attachment members indicated by numeral 32.

The said extensible attachment members 32 as shown in Figure 9 are provided with an arm member 33 which is twisted so as to present a flat surface for connection to the link member 34. The link member 34 is pivotally connected at one end by the rivet 35 to the adjacent end of the arm member 33 and the said link member is pivotally fastened at the other end by the

rivet 36 to the adjacent end of the primary attachment bar.

The arm member 33 of the attachment member 32 approximates the length of the link member 34. The attachment member 32 may be readily retracted independently of the grille proper by merely pivoting the link member 34 together with the arm member 33 so that the same are brought together in a closed position as shown in Figure 9. The said extensible adjustment member of Figure 9 is shown in dotted lines in a second adjusted position. Moreover the attachment member 32 may be readily extended independently of the extensible grille proper by pivoting the arm member 33 and the link member 34 so as to place the same in longitudinal alignment as shown in Figures 2 and 5.

A second form of my invention is illustrated in Figures 4, 5 and 6. The latter form of my invention has provided the base bar structure including the primary base bars 37, 38, 39 and 40.

The said primary base bars are pivotally connected in series at the opposite ends thereof as at 41 so as to form a quadrangle having sides of equal length as shown in Figures 4 and 10.

There are further provided the attachment bars 42, 43, 44 and 45 having as shown in Figure 4 the fixed attachment member 46 provided at one end and the extensible attachment member 32, previously described, provided at the opposite end.

The bars 42 and 43 extend parallel to and in spaced relation to the base bars 37 and 39 and the said bars are spaced an equal distance apart.

35 The bars 42 and 43 extend in crosswise relation to the base bars 38 and 40. The attachment bars 44 and 45 extend in crosswise relation to the base bars 37 and 39 and the attachment bars 42 and 43. The attachment bars 44 and 40 45 extend parallel to and in spaced relation to the base bars 38 and 40. The said bars 40, 43, 45 and 38 are spaced an equal distance apart. The base bars and the attachment bars at the points of crossing are pivotally connected by rivet or 45 other suitable means.

As shown in the disclosure of Figure 4 the extensible attachment members 32 are provided for attachment to the upper and lower frame of the window, while the fixed attachment members 46 are shown for attachment to the sides of the window frame.

However, in either the form of my invention illustrated in Figures 1, 2 and 3 or Figures 4, 5 and 6 the extensible attachment members may obviously be placed at the sides instead of the top or the grille may be constructed with extensible attachment members at the sides as well as the top.

The attachment members are fastened to the 60 top side and bottom frame of a door or window by screws as shown or in any other suitable manner well known in the art.

It will be readily seen that in the mechanical arrangement of my grille disclosed in Figure 4 that as the grille is extended or retracted the fixed side fastening members will be equally adjusted and will remain in alignment with the side frame of the door or window. Likewise, it will be seen that in the form of my invention illustrated in Figure 1 there has been combined in a novel manner the mechanical features of two of the grilles shown in Figure 4. Thus the primary base bars 1 and 2 of the Figure 1 disclosure represent an extension of the base bars 37 and 40 of the disclosure in Figure 4 and the

supplemental base bars 8 and 9 in the upper quadrangle of Figure 1 correspond to the attachment bars 43 and 45 of Figure 4, while the supplemental base bars 10 and 11 of the lower quadrangle of Figure 1 correspond to the attachment bars 42 and 44 of Figure 4. Obviously following the teaching of my application any number of combinations of the grille unit disclosed in Figure 4 may be made either in series vertically, horizontally or both.

As the form of my grille disclosed in Figure 1 is extended or retracted as shown in Figures 2 and 3, the mechanical arrangement of the said grille will cause the fixed side attachment members 18, 28, 30 and 31 and the side attachment members 19, 29, 31 and 20 to be equally adjusted so that the same remain in parallel alignment at all times with the frame of the door or window.

Further it will be seen that due to the novel mechanical arrangement of the base bars whereby the same are pivotally connected at the longitudinal ends thereof, there is permitted the greatest extension and contraction of my grille as shown in Figures 2, 3, 5 and 6.

Furthermore in positioning the attachment members as shown in Figures 1 and 4, at either side of the pivotal connection of the base bars, there has been provided the maximum protection for the door or window and support for the grille with the minimum number of members to be attached, thereby lessening the cost of production and the labor required to install such a grille in a door or window.

Moreover, the feature of my invention of the extensible attachment members provides means for a vertical adjustment of the grille without the necessity of horizontal adjustment and further provides means for the adjustment of the position of the attachment members in making such adjustment so that the same may be positioned so as to afford the maximum protection and support to the door or window.

Having thus described my invention, what I claim as my invention and desire to secure by Letters Patent is:

1. A grille comprising a pair of pivotally intercrossing primary base bars, two pairs of secondary base bars, the secondary base bars of each pair being pivotally connected together at one of the longitudinal ends of each of the said secondary base bars, and the other longitudinal end of one of each pair of secondary base bars being pivotally connected to the longitudinal end of one of the said intercrossing primary base bars, and the other secondary base bar of each pair having the other longitudinal end thereof pivotally connected to the longitudinal end of the other of the said interconnecting primary base bars, said primary and secondary base bars thereby forming a pair of adjustable quadrangles, attachment bars pivotally connected to the said base bars intermediate the longitudinal ends of the said base bars, attachment members mounted on the said attachment bars and positioned in spaced relation to each other, whereby the said grille may be freely adjusted to the opening of a door or window of varying size and the attachment members adjusted in alignment with the frame of the said door or window.

2. A grille comprising two pairs of base bars, attachment members positioned in spaced relation to each other and mounted on the said base bars, the base bars of each pair pivotally intercrossing each other, and each of the base bars of

each pair having one of the longitudinal ends thereof pivotally connected to the longitudinal end of one of the base bars of the other pair, and other intercrossing bars pivotally connected to said base bars, whereby the said grille may be freely adjusted to the opening of a door or window of varying size.

3. A grille comprising two pairs of base bars, the base bars of each pair pivotally intercrossing each other, and each of the base bars of each pair having one of the longitudinal ends thereof pivotally connected to the longitudinal end of one of the base bars of the other pair and the opposite free portions of each of the said base bars extending outwardly from the point of pivotal intercrossing of the said base bars of each pair, two pairs of attachment bars, the attachment bars of each pair pivotally intercrossing and having attachment means provided at the opposite ends thereof, and the attachment bars of one pair pivotally connected to the said free portions of the base bars of one pair of the said base bars and the other pair of the said attachment bars pivotally connected to the said free portions of the base bars of the other pair of the said base bars, and the attachment means provided at the opposite ends of said one pair of attachment bars arranged in spaced relation to the attachment means provided at the opposite ends of said other pair of attachment bars for the free movement of said one pair of attachment bars in relation to the other pair of attachment bars, whereby the said grille may be adjusted and the attachment means aforesaid adjusted in alignment with the frame of an opening for fixation thereon.

4. A grille comprising a pair of intercrossing primary base bars, two pairs of secondary base bars, the secondary base bars of each pair being pivotally connected together at the adjacent longitudinal ends thereof, the other longitudinal ends of each pair of secondary base bars being pivotally connected one end to a longitudinal end of one of the said intercrossing primary base bars and the other end pivotally connected to a longitudinal end of the other intercrossing primary base bar, two pairs of supplemental base bars, the base bars of each pair of supplemental base bars pivotally intercrossing each other, and each of the supplemental base bars of each pair having one of the longitudinal ends thereof pivotally connected to the longitudinal end of one of the supplemental base bars of the other pair, attachment means provided at the other end of the said supplemental base bars, and the said supplemental base bars pivotally connected to the said primary base bars, two pairs of attachment bars, the attachment bars of each pair pivotally intercrossing and having attachment means provided at the opposite ends thereof, and the attachment bars of one pair pivotally connected to one pair of the said secondary base bars and the other pair of the said attachment bars pivotally connected to the other pair of the said secondary base bars, whereby the said grille may be adjusted and the attachment means aforesaid adjusted in alignment with the frame of an opening for fixation thereon.

5. A grille comprising a pair of intercrossing primary base bars, two pairs of supplemental base bars, the base bars of each pair of supplemental base bars pivotally intercrossing each other, and each of the supplemental base bars of each pair having one of the longitudinal ends

thereof pivotally connected to the longitudinal end of one of the supplemental base bars of the other pair, attachment members provided at the other end of the said supplemental base bars, and means pivotally connecting the said supplemental base bars to the said primary base bars, two pairs of attachment bars, the attachment bars of each pair pivotally intercrossing, attachment members provided at the opposite ends of said attachment bars, each of the said attachment bars pivotally connected to one of the said primary base bars, and each of said attachment members arranged in spaced relation to the other of said attachment members, whereby the said grille may be adjusted for fixation to the frame of a door or window.

6. A grille comprising two pairs of attachment bars, each pair of attachment bars pivotally intercrossing the other pair, link members, each of said link members laterally pivoted to an end of the said attachment bars, attachment arms laterally pivoted to the said link members and curled attachment members mounted on the said attachment arms, whereby the said curled attachment members of the said grille may be adjusted and the said attachment arms adjustably positioned.

7. A grille comprising a set of intercrossing primary base bars, attachment bars pivotally intercrossing the said base bars, a link member connected at one of the longitudinal ends of each of the said attachment bars in such a manner as to pivot laterally, an attachment member connected to each of the said link members so as to pivot laterally thereto, whereby upon pivotal movement of the said link members the said attachment members may be adjustably extended.

8. A grille comprising a plurality of base bars, each of the said base bars having another base bar pivotally connected at the opposite longitudinal ends thereof and the said interconnected base bars forming a quadrangle, attachment bars pivotally connected to the said base bars, intermediate the longitudinal ends of the said base bars, laterally pivoted extensible attachment means including fastening members and laterally pivoted link members, each of said

link members pivotally connected at opposite ends to an end of the said attachment bars and to an end of the said fastening member so as to effect adjustment of the said attachment means to the opening of a door or window of varying size and shape.

9. A grille comprising two sets of connected intercrossing bars, attachment members, laterally pivoted link members, each of said link members pivotally connected at opposite ends to an end of the said bars and to an end of the said attachment members whereby the said attachment members may be adjusted to effect attachment of the said grille to the frame of an opening of varying size and shape.

10. A grille comprising in combination a pair of intercrossing primary base bars, two pairs of secondary base bars, the secondary base bars of each pair being pivotally connected together at the adjacent longitudinal ends thereof, the other longitudinal ends of each pair of secondary base bars being pivotally connected one end to a longitudinal end of one of the said intercrossing primary base bars and the other end pivotally connected to a longitudinal end of the other intercrossing primary base bar so as to form a pair of adjustable quadrangles, two pairs of supplemental base bars, the base bars of each pair of supplemental base bars pivotally intercrossing

20 30 35 40 45 each other, and each of the supplemental base bars of each pair having one of the longitudinal ends thereof pivotally connected to a longitudinal end of one of the supplemental base bars of the other pair so as to form a third adjustable quadrangle, attachment members mounted at the other ends of said supplemental base bars, each of said attachment members positioned in spaced relation and freely movable in relation to the other of said attachment members, and means operably connecting said supplemental base bars to said primary base bars, said primary, secondary and supplemental base bars thereby forming a plurality of operably connected adjustable quadrangles, whereby said grille may be adjusted and the attachment members aforesaid positioned in alignment with the frame of an opening for fixation thereon.

DALLAS E. WALKER.
